Primary Examiner—Louis S. Zarfas*Assistant Examiner*—Gregory Andoll*Attorney, Agent, or Firm*—Sughrue, Mion, Zinn, Macpeak & Seas, PLLC**[57] CLAIM**

The ornamental design for an auxiliary finger flange for a syringe, as shown and described.

DESCRIPTION

FIG. 1 is a perspective view of the front, bottom and one side of an auxiliary finger flange for a syringe showing my new design;

FIG. 2 is a bottom plan view thereof;

FIG. 3 is a front elevational view thereof;

FIG. 4 is a side elevational view of said one side thereof, the opposite side being a mirror image thereof;

FIG. 5 is a top plan view thereof; and,

FIG. 6 is a rear elevational view thereof.
